UNITED STATES PATENT OFFICE.

KELSO MURDOCK, OF CINCINNATI, OHIO, ASSIGNOR TO THE MURDOCK MANUFACTURING AND SUPPLY CO., OF CINCINNATI, OHIO, A CORPORATION OF OHIO.

SUPPLY AND DRAIN CAP FOR ANTIFREEZE HYDRANTS.

1,385,572.

Specification of Letters Patent. Patented July 26, 1921.

Application filed March 5, 1920. Serial No. 363,619.

To all whom it may concern:

Be it known that I, KELSO MURDOCK, a citizen of the United States of America, and a resident of Cincinnati, in the county of 5 Hamilton and State of Ohio, have invented a new and useful Improvement in Supply and Drain Caps for Antifreeze Hydrants, of which the following is a specification.

The object of my invention is to provide 10 a supply and drain cap in which the drains will not clog from the clay or foreign substances that may be placed around or about the cap when the hydrant is installed. Another object is to provide a cap that will be 15 less apt to become lost in shipment than those now used.

These and other objects are attained by the means described hereinafter and disclosed by the following drawings, in which: 20 Figure 1 is a plan view of a combined supply and drain cap embodying my invention.

Fig. 2 is a sectional view on line 2--2 of Fig. 1.

Fig. 3 is a front elevation of a cap embodying my invention.

My invention comprises a combined supply and drain cap for anti-freezing hydrants having lugs extending from points 30 near the upper edge of its outer surface, a rib on the bottom, and a series of apertures through the sides and the bottom. The cap 35

A has a supply pipe connection a extending through its wall and having appropriate connection ends a^{12} and a^{13} . This supply pipe is supported internally by a bracket a' . Lugs a^2 and a^3 project outwardly from the cap side wall a^6 at diametrically opposed 40 points near the top a^{14} . Directly below the lugs and at the intersection of the side wall a^6 and the base a^8 are apertures a^4 and a^5 . These apertures extend for a short distance 45 over both the wall and the base. A rib a^9 formed on the exterior of the bottom or base extends preferably diametrically across the base from points adjacent to the apertures a^4 and a^5 . Apertures a^{10} and a^{11} are formed in the bottom of the cap, on either side of the rib a^9 . The cap is adapted to be seated 50 on the bottom of a hydrant by means of screw threads a^7 .

The operation of the device is as follows: The water supply enters the hydrant through the supply pipe a . The waste water will 55 fall to the bottom of the cap and will drain through the apertures a^4 , a^5 , a^{10} , and a^{11} .

The lugs a^2 and a^3 serve to hold such substances as bricks or stone that might be thrown against or around the cap at the base of the hydrant, when it is installed, 60 from closing the apertures a^4 and a^5 on their side exposures. The rib a^9 will sit on any substance that may be at the base of the installed hydrant, thereby leaving a clearance space between the substance on which 65 it may be seated and the base. This clearance space will prevent clay or mud from clogging up the apertures and will therefore permit the water to drain away through the sand or other substances at the base of 70 the hydrant.

Having described my invention, what I claim is:

1. A combined supply and drain cap, having side walls and a base, for hydrants, and 75 having a series of drain perforations through its side walls and base, lugs extending from the side walls above the side perforations, and a rib formed on the exterior of the base adjoining the perforations in the base. 80

2. A combined supply and drain cap, having side walls and a base, for hydrants, and having a series of drain perforations through its base and having a series of perforations extending through both a part of its base 85 and its side walls, a rib formed on the exterior of the base and lugs projecting, from the exterior of the side walls, above the perforations.

3. A combined supply and drain cap, having a base and side walls, for hydrants, and 90 having a series of drain perforations through its base and having a rib formed across the exterior of the base.

4. A combined supply and drain cap, having side walls and a base, for hydrants, and having a series of drain perforations through its side walls, and having lugs projecting from the exterior of the side walls above the perforations. 95

5. A combined supply and drain cap, having side walls and a base, for hydrants, and having drain perforations therethrough at the junction of the side walls and the base, and lugs projecting from its exterior and adapted to space foreign matter from the perforations. 105

In witness whereof, I have hereunto subscribed my name this 2nd day of March, 1920.

KELSO MURDOCK.
